UNITED STATES PATENT OFFICE

EDWARD H. COOLEY, OF CAMBRIDGE, MASSACHUSETTS

ARTICLE OF FURNITURE

Application filed July 16, 1929. Serial No. 378,705.

My invention relates to articles of furniture, and more particularly to a convertible structure adapted to serve selectively the purposes of a plurality of articles of furniture.

More specifically, and in one form of embodiment, my invention relates to a combination desk and table, comprising a structure provided with a foldable top, adapted to be extended when the structure is to be used as a table, and to be retracted and wholly or partially concealed from view when it is desired to convert the structure into a desk.

An object of my present invention is to provide a piece of furniture of the character indicated which is simple, durable and inexpensive in construction and whose parts may be readily and easily manipulated into their several operative positions.

Other and further objects of the present invention will sufficiently appear as the description proceeds.

In the drawings hereto appended which form part of this application for Letters Patent, and in which like reference characters indicate the same parts in the several views:

Figure 1 is a perspective view of one form of embodiment of my present invention with the parts disposed for use as a desk;

Fig. 2 is an end elevation of the structure shown in Fig. 1;

Fig. 3 is a similar view of the same structure with the top extended to form a table of one form;

Fig. 4 is a front elevation of the structure shown in Fig. 3, but with the top rotated through 90° to form a table of another form;

Fig. 5 is a perspective view of the table shown in Fig. 4, showing certain concealed parts in dotted lines;

Fig. 6 is a front elevational view of a modified form of embodiment of my invention when in use as a desk; and

Fig. 7 is a view similar to Fig. 6 but showing the manner of converting the desk shown in Fig. 6 into a table.

Referring to the drawings, 1 indicates generally an article of furniture having legs, a top, and if desired, drawers. This article of furniture may be designed for use as a desk, 50 buffet, bureau, table or the like. In each fig-

ure of the drawings I have shown this much of the structure embodied in a form suitable for use as a desk, but it is to be understood that my invention is by no means limited to use in connection with desks. Any type of furniture having a plane top surface may serve as the under structure of a piece of furniture constructed according to the principles of my present invention. The desk structure shown in the accompanying drawings is intended to be merely by way of exemplification, and it is to be understood that the word "desk" as used in this application for Letters Patent is intended to include any article of furniture having a plane top surface, as above specified.

Mounted on the under top 2 of the desk is a desk top 3, which may be rotated through 90° or more about a pivot 4 fixed in the under top. In a desk structure having an oblong top such as those illustrated in the drawings, this pivot is positioned either centrally of the top, as shown in Figures 1 to 5, inclusive, or eccentrically thereof, as shown in Figures 6 and 7. The purpose of so locating the pivot, and the effect of positioning it centrally or eccentrically, will be hereinafter explained.

Along the rear edge of the desk top 3, a hinge or series of hinges 5 serves to connect to the desk top one leaf 6 of a table top. A companion leaf 7 is hinged to leaf 6 along their upper horizontal edges, as shown in Fig. 1, by means of the hinges 8. I prefer to employ hinges 8 of the type used on spinet desks, as shown in the drawings, which will allow the two hinged edges of the leaves 6 and 7 to make flush contact with each other and lie in a single plane when in their extended position, as shown to advantage in Figures 3, 4, 5 and 7.

When it is desired to convert a desk as shown in Fig. 1, into a table, leaves 6 and 7 are rotated through 90° about hinge 5 to place them in planes parallel with that of the desk top 3. Rear leaf 7 may then be rotated through 180° about the hinges 8 to dispose it in the same plane as leaf 6, as shown in Fig. 3, and then the two leaves, together with desk top 3, rotated through 90° about the pivot 4 to assume the position shown in Figs. 100

4 and 5; or, if desired, after leaves 6 and 7 are lifted into parallel, superposed horizontal planes, they may be rotated with desk top 3 through 90° about pivot 4, and then opened up by rotating upper leaf 7 through 180° about the hinges 8 to assume the position shown in Figs. 4 and 5. Whichever mode of operation is followed, there results a table having a width equal to the length of the leaves 6 and 7, and a length equal to twice their height when in the retracted positions shown in Fig. 1. Small support blocks 9 of a thickness equal to the thickness of the desk top 3 are secured to the under sides of the leaves 6 and 7 to fill the space between the leaves and the under top 2 when the leaves are in their extended position. Spacer blocks 10, having an upper beveled or rounded edge, are secured to the rear of the supporting structure 1 just below the under top 2 for the purpose of camming the leaves 6, 7, into accurate vertical relation to the desk top 3 when retracted, and thereby urge the front edges of tops 2 and 3 into parallelism.

It will be noted that the structure illustrated in Figures 6 and 7 differs in two respects from that shown in the other figures; first, the pivot 4 is positioned eccentrically of the desk top 3; and secondly, the leaves 6 and 7 when in their folded back position extend only to the level of the desk top 3. I have discovered that a constant inverse relation exists between the degree of eccentricity of the pivot 4 and the height above the desk top of the leaves 6 and 7, or in other words, the farther the pivot 4 is removed from the geometrical center of the desk top 3, the smaller will be the height of the leaves 6 and 7 projecting above the desk top 3. Figures 6 and 7 show the pivot 4 placed at its position of maximum allowable eccentricity, so that the upper edges of the leaves 6 and 7 when in their folded back positions are flush with the level of the desk top. It will be apparent that when the pivot is located at any point intermediate between the positions shown in Figures 4 and 6, the height of the leaves 6 and 7 above the level of the desk top 3 will vary accordingly.

It will be appreciated that in the eccentric pivot form it is desirable to employ a desk top whose long dimension is exactly twice its short dimension, and which is of course of rectangular shape, so that when the desk top is rotated 90° about the pivot the hinge 5 will lie along the transverse axis of the under top 2, making the top formed by the extended leaves 6 and 7 symmetrical with the under top. I accomplish this symmetrical positioning of the extended leaves by locating the eccentric pivot 4 at a point in the desk top 3 which is at once equidistant from the longitudinal and transverse axes of the desk top and from the rear or hinged edge thereof. This is the point of maximum eccentricity of the pivot. Intermediate points for the location of the eccentric pivot lie along a line joining this point with the center of the desk top, or in other words, a line which bisects the angle formed by the intersection of the two axes of the desk top.

Conversion of a desk as shown in Fig. 6 to a table is accomplished in the same manner as the structure shown in Figures 1 to 5, inclusive, i. e., the leaves are lifted to a horizontal position, the desk top is then rotated 90° about the pivot 4, and the upper leaf swung through 180° to lie in the same plane as the other leaf, as indicated in Fig. 7.

It will be apparent that variation in the degree of eccentricity of the pivot 4 varies inversely the length of the table top when the leaves are in their extended position, i. e., with the pivot centrally positioned a table top of maximum length is obtained, while location of the pivot 4 at the point of maximum eccentricity provides a table top of minimum length.

It is to be noted that in the eccentrically pivoted form of structure shown in Figs. 6 and 7, only one support block 9 is required, since the rotated desk top 3 sufficiently underlies the leaf 7 when in its extended position, as clearly shown in Fig. 7.

A further modification is indicated by dotted lines in Fig. 1, to provide an article of furniture having an extended table top which will be narrower than those previously described. According to this form of the invention, the desk top 3 is made in three parts, consisting of fixed end portions and a central pivoted portion, the latter being bounded by curved edges 11, 12, which are arcs of a center formed by the pivot 4. The length of the leaves 6, 7, may then be reduced to a length equal to the diameter of the rotatable portion of the desk top, as indicated by the dotted lines 13, 14. Hinges 8 will necessarily be located in approximately their dotted line position in Fig. 1.

The advantages and mode of operation of an article of furniture with parts so constructed will be obvious, the leaves being raised and turned to form an extended table top exactly as has been explained in connection with the previously described forms of embodiment. In the present modification, supporting blocks 9 are dispensed with, the fixed end portions of the desk top adequately serving their purpose. It will be evident that the reduction in the length of the leaves will result in forming a narrower table top when the leaves are in their extended position, while the reduction of the dimensions of the rotatable portion of the desk top will prevent any portions thereof from extending beyond the edges of the table top when the leaves are in their extended position.

It is to be understood that my present invention is capable of exemplification in other

and further modifications not shown or described in this application for Letters Patent, but all such modifications in so far as they embody the principle of the present invention 5 are to be deemed within the scope and purview of the appended claims.

What I claim and desire to secure by Letters Patent is:

1. An article of furniture comprising a supporting structure having an under top, a desk top rotatably mounted thereon, and a plurality of leaves hinged to each other and to one edge of the desk top.
2. An article of furniture comprising a supporting structure having an under top, a desk top overlying the under top and pivoted thereto, and a plurality of leaves hinged together, one of said leaves being hinged to the desk top.
3. An article of furniture comprising a supporting structure having an under top, a rectangular desk top having a length twice as great as its width overlying the under top and pivoted thereto at its center, and a plurality of leaves hinged to each other and to one edge of the desk top.
4. An article of furniture comprising a supporting structure having an under top, a rectangular desk top overlying the under top and pivoted thereto at a point equidistant from the longitudinal and transverse axes thereof, and a plurality of leaves hinged to each other, one of said leaves being hinged to the desk top.
5. An article of furniture comprising a supporting structure having an under top, a desk top overlying the under top and rotatably mounted thereon, a plurality of leaves hinged to each other and to one edge of the desk top and normally depending therefrom, and a hinge connection between said leaves whereby said leaves are adapted to overlie the desk top in a single plane when lifted to a horizontal position.

45 In testimony whereof I affix my signature.
EDWARD H. COOLEY.
